UNITED STATES PATENT OFFICE.

ABNER HARVEY GRAGG, OF KNOXVILLE, TENNESSEE.

CHURN.

No. 874,002.

Specification of Letters Patent.

Patented Dec. 17, 1907.

Application filed February 28, 1907. Serial No. 359,793.

To all whom it may concern:

Be it known that I, ABNER HARVEY GRAGG, a citizen of the United States, residing at Knoxville, in the county of Knox and State of Tennessee, have invented a new and useful Improvement in a Churn, of which the following is a specification.

This invention relates to churning and more particularly to reciprocating churning; the object being to provide a churn which is very simple and cheap in construction, and which is very effective in operation.

Another object of my invention is to provide a very novel mechanism for reciprocating the blades alternately.

With these and other objects in view, the invention consists in the novel features of construction, combination and arrangement of the parts hereinafter fully described and 20 pointed out in the claims.

In the drawing forming a part of this specification:—Figure 1 is a vertical sectional view through the churn. Fig. 2 is a side elevational view of the churn. Fig. 3 is a section taken on the lines 3—3 of Fig. 1. Fig. 4 is a top plan view of the churn. Fig. 5 is a perspective view of one of the rods carrying the blades.

Referring to the drawing A indicates a 30 churn body provided with a removable top B, on which are mounted the flanged ends of U-shaped frames C and D, which are connected together at one end, by a bar E having flanged ends. Angle-bars F and G are 35 connected to the opposite ends of the reciprocating frames having angled ends, which are connected to the bar E, and the frames are connected together at said ends by a bar E'. One end of the bar G projects out beyond the frame C having a boss G', formed on its end, in which is mounted a shaft H carrying a gear-wheel H' provided with a handle H² by means of which it is turned.

Mounted on a shaft I between the bars F 45 and G, is a gear-wheel I' which meshes with the gear-wheel H', and a gear-wheel J secured on a shaft K which is also mounted between the bars F and G, and is provided with crank-arms K', K² at their ends. Wrist pins are secured in the end of the crank-arms

on which are mounted pitman rods L and M provided with angled apertured ends.

A central opening is formed in the top B in which works a hollow shaft N provided with an outwardly projecting pin N' at its upper end, on which is secured the apertured ends of the pitman rod L, by a nut N². The lower end of the shaft is provided with a flange M³ having oppositely disposed openings formed therein, in which are secured the threaded ends of rods O, by nuts O' which are provided with spaced horizontal blades O² forming beaters. The depending end of the pitman rod M is secured on a pin P' projecting out from the upper end of a shaft P, by a nut P² and extends down through the shaft N having an enlarged lower end P³ provided with a vertical bore in which works a guide-pin Q projecting up centrally from the bottom of the churn body, 70 so that the shaft will be held centrally in the churn, which reciprocated. Oppositely disposed horizontal blades P⁴ project out from the shaft P which are so arranged that when the blades are reciprocated, they work in 75 between the blades O². Staples R project out from the enlarged end P³ of the rod P, and embrace the rods and prevent the same from spreading.

Having thus fully described my invention, 80 what I claim as new and desire to secure by Letters Patent is:—

1. In a churn, the combination with a body provided with a removable top, of frames mounted on said top, a shaft mounted 85 in said frame provided with crank-arms, pitman rods carried by said crank-arms, a hollow shaft carried by one of said pitman rods, working through an opening in the said top, rods carried by said shaft, provided with 90 a series of spaced blades, a shaft carried by the other pitman rod provided with a series of spaced blades, and means for operating said crank-shaft.

2. In a churn, the combination with a 95 body provided with a removable top, of frames mounted on said top, a gear wheel mounted on said frame provided with a handle, a gear meshing with said gear mounted in the frame, a shaft mounted in the frame 100

carrying a gear meshing with said gear, | crank arms carried by said shaft, pitman rods carried by said crank-arms, a hollow shaft carried by one of said pitmen extend-
5 ing through said top, carrying rods provided with blades, and a shaft carried by the other pitman working through the hollow shaft

| provided with blades, and provided with a bore in its end working over a guide-pin projecting up from the bottom of the churn. 10
